CLAIM

The ornamental design for an oral care applicator, as shown and described.

DESCRIPTION

FIG. 1 is a perspective view of an oral care applicator, embodying the new design;

FIG. 2 is a front view thereof;

FIG. 3 is a back view thereof;

FIG. 4 is a left view thereof;

FIG. 5 is a right view thereof;

FIG. 6 is a top view thereof and

FIG. 7 is a bottom view thereof;

FIG. 8 is a perspective view of an oral care applicator, embodying the new design;

FIG. 9 is a front view thereof;

FIG. 10 is a back view thereof;

FIG. 11 is a left view thereof;

FIG. 12 is a right view thereof;

FIG. 13 is a top view thereof and

FIG. 14 is a bottom view thereof;

FIG. 15 is a perspective view of an oral care applicator, embodying the new design;

FIG. 16 is a front view thereof;

FIG. 17 is a back view thereof;

FIG. 18 is a left view thereof;

FIG. 19 is a right view thereof;

FIG. 20 is a top view thereof and

FIG. 21 is a bottom view thereof;

FIG. 22 is a perspective view of an oral care applicator, embodying the new design;

FIG. 23 is a front view thereof;

FIG. 24 is a back view thereof;

FIG. 25 is a left view thereof;

FIG. 26 is a right view thereof;

FIG. 27 is a top view thereof; and,

FIG. 28 is a bottom view thereof.

The broken line shown in the figures is included for the purpose of illustrating portions of the oral care applicator and forms no part of the claimed design.
